UNITED STATES PATENT OFFICE

CHRISTIAN AUGUSTUS ALBRECHT, OF BERLIN, GERMANY, ASSIGNOR TO MERGEN-
THALER LINOTYPE COMPANY, OF BROOKLYN, NEW YORK

TYPOGRAPHICAL COMPOSING AND LINE-CASTING MACHINE

Application filed January 9, 1932, Serial No. 585,669, and in Germany August 31, 1931.

This invention relates to typographical composing and line-casting machines of the known construction in which matrices are released from a magazine by the depression 5 of keys which, together with certain of the members which transmit the movement onward from the keys, are located in a keyboard. In order to make this keyboard more easily accessible, and more especially those 10 parts thereof located at the back, it has already been proposed to movably mount the keyboard on pivots so as to permit it to be swung out of its operative position. It has also been proposed to mount the keyboard 15 on the machine frame so that it can be moved rectilinearly in lateral or sidewise direction.

The object of the present invention is a still further development of the movable keyboard. In machines wherein the keyboard 20 is movable in lateral direction, it has been found, after the keyboard has been moved from its operative position, that the space available at the back of it, for inspection or the making of repairs is comparatively small unless the lateral guides on which the keyboard is supported, are unreasonably long, which arrangement is not generally practicable especially in cases where the accommodation is somewhat restricted. 25 As a matter of fact it is quite customary in narrow composing rooms to arrange the machines side by side as closely as possible. In the case however, of machines aligned in fore and aft direction, there usually exists 30 a greater amount of space between them, as room has to be provided for the operator's seat and for access thereto, whilst the back of the machine must always remain accessible.

According to the present invention, the keyboard is moved rectilinearly in fore and aft direction, that is to say, towards and away 35 from the operator. In order that the guides for the keyboard shall not be in the way, it is preferable for them to be movable or tilt-

able so that they will not project beyond the front edge of the keyboard when the latter is in operative position.

The drawing illustrates one preferred constructional form of the invention, and in the 50 said drawing:—

Figure 1 is a side elevation, and

Figure 2 a front elevation of the pertinent parts of a matrix composing and line casting 55 machine.

The keyboard *a* is constructed in the customary manner. When a key is depressed, the releasing rod controlled thereby, is raised, the releasing rods being divided in the usual manner. The lower portion *k*¹ of the releasing rods, is mounted in a guide on the keyboard itself and is movable with the keyboard, whilst the upper portion *k*² is guided in a comb *f* which is rigidly connected to the machine frame *m* by means of two side brackets *g*. 60

According to the invention, the keyboard is movable in fore and aft direction from the foremost or inoperative position in which it is shown in dotted lines in Figure 1 into the 70 operative position in which it is shown in full lines in that figure, and vice versa. For this purpose, the keyboard is mounted upon two side rails *n*. These rails rest upon duplicate sets of rollers *o* which are pivoted in the 75 machine frame and serve to support the keyboard with a capacity for being moved backwards and forwards. In order to prevent the keyboard from overbalancing when it is in its foremost position, a further roller *p* is provided on each side of the keyboard on upwardly extending arms of the frame *m*, the said rollers bearing upon the upper surfaces of the rails *n*. The rollers *o* and *p* are provided with flanges *o*¹, *p*¹ to prevent the keyboard slipping off the rollers laterally, or, 80 obviously, other means may be provided for this purpose. Further, both the rails *n* can be rigidly connected together to form a 85 frame-like structure, by means of a trans-

verse member such as a plate q . It is obvious that the means for moving the keyboard or for guiding it might be constructed differently. For instance, instead of the guide rails being attached to the keyboard a , they may be hinged to the front of the machine frame, so that they can be swung upwardly and secured in an operative position when required to serve as a runway for the keyboard as when the latter is to be pulled forward, and swung downwardly to an inoperative position when not so required for supporting the keyboard. Rails slidable independently of the keyboard and movable in and out of the machine frame could also be used as guides.

The direction of movement of the keyboard need not necessarily be directly fore and aft, for, by arranging the supporting rails at the desired angle in the machine frame, the keyboard may be moved obliquely frontwise so as to obtain at the same time a little more space at the side. A saving in lateral space would also result in such a case because when the keyboard is moved obliquely towards the front and towards one side, the lateral movement need be only sufficient to enable free access to be had to all parts of the keyboard.

Having described my invention, I declare that what I claim and desire to secure by Letters Patent is:—

1. Matrix composing and line casting machine in which the keyboard can be moved out of its operative position for the purpose of making it more accessible, characterised by the fact that the keyboard is mounted on the machine frame so as to be movable in fore and aft direction towards and away from the operator.

2. Matrix composing and line casting machine according to claim 1, characterised by mutually engaging members on the keyboard and on the machine frame, which retain the former on the latter with a capacity for said former to be moved in fore and aft direction relatively to the latter.

3. In a keyboard controlled matrix composing and line casting machine, the combination with the keyboard, of rails fast thereto and extending in fore and aft direction, and rollers on the machine frame, supporting the rails with a capacity for said rails to be moved in the direction of their length.

4. In a keyboard-controlled matrix composing and line casting machine in which the keyboard is movable in fore and aft direction relatively to the machine frame, the combination with the keyboard, of rails fast thereto and extending in fore and aft direction, and rollers on the machine frame acting on the rails to prevent them and the keyboard from overbalancing when the keyboard is in its foremost position.

5. Matrix composing and line casting machine according to claim 1, characterised by the fact that the keyboard is mounted on rails united into a frame, the said rails being movable backwards and forwards in the machine frame and so supported as by rollers, that in their foremost position they and the keyboard will be prevented from overbalancing.

In witness whereof I have affixed my signature hereto.

CHRISTIAN AUGUSTUS ALBRECHT.
